Patented Aug. 23, 1960

188,674

BALL RETURN RISER OR THE LIKE

Richard G. Reineman, Covina, Calif., George E. Schaefer, Muskegon Heights, Mich., and George H. Hart, Chicago, Ill., assignors to Brunswick Corporation, a corporation of Delaware

Filed Apr. 18, 1960, Ser. No. 60,220

Term of patent 14 years

(Cl. D34—5)

Fig. 1 is a perspective view of a ball return riser or the like showing our new design;

Fig. 2 is an enlarged side elevational view thereof;

Fig. 3 is a top plan view thereof; and

Fig. 4 is an end elevational view thereof, taken from the left of Fig. 2.

We claim:

The ornamental design for a ball return riser or the like, as shown.
